US00D382550S

United States Patent [19]

Kaneko et al.

[11] Patent Number: Des. 382,550

[45] Date of Patent: **Aug. 19, 1997

[54] REAR PORTION OF A POINTING DEVICE

[75] Inventors: **Steven T. Kaneko**, Seattle; **Carl J. Ledbetter**, Lynnwood; **Edie Adams**, Seattle; **Kabir Siddiqui**, Redmond, all of Wash.

[73] Assignee: **Microsoft Corporation**, Redmond, Wash.

[**] Term: **14 Years**

[21] Appl. No.: **48,728**

[22] Filed: **Jan. 16, 1996**

Related U.S. Application Data

[63] Continuation-in-part of Ser. No. 49,616, Jan. 5, 1996.

[51] LOC (6) Cl. **14-02**

[52] U.S. Cl. **D14/114**

[57] CLAIM

The ornamental design for a rear portion of a pointing device, as shown and described.

DESCRIPTION

FIG. 1 is a rear isometric view of a rear portion of a pointing device showing our new design;

FIG. 2 is a top plan view thereof;

FIG. 3 is a front elevational view thereof;

FIG. 4 is a left side elevational view thereof;

FIG. 5 is a right side elevational view thereof; and,

FIG. 6 is a top plan view of an alternative embodiment of the rear portion of a pointing device of FIG. 1.

The broken lines are for illustrative purposes only and forms no part of the claimed design.
